UNITED STATES PATENT OFFICE.

HAROLD SERRELL, OF PLAINFIELD, NEW JERSEY.

ALARM-BELL FOR BICYCLES.

SPECIFICATION forming part of Letters Patent No. 285,933, dated October 2, 1883.

Application filed March 29, 1883. (No model.)

To all whom it may concern:

Be it known that I, HAROLD SERRELL, of Plainfield, in the county of Union and State of New Jersey, have invented an Improvement 5 in Alarm-Bells for Bicycles, and the following is declared to be a description of the same.

Alarm-bells for bicycles have been constructed for use upon both the handle-bar of the machine and the upright arm of the brake. Most 10 of these bells are adapted to give a single stroke. Some will give several vibrations of the hammer for each pull of the lever, and some are operated by a roller running upon the rubber tire of the large wheel of the machine, 15 and when brought into action give out a continuous alarm until released.

The object of my invention is to provide an alarm-bell for bicycles that is adapted to be actuated at either the handle-bar or the brake-arm of the machine, and that will give an alarm of greater or less duration at the discretion of the rider, or which may be continued in operation until run down, and which may be wound up by the rider.

25 My invention consists in an alarm-bell for bicycles in which a spring is employed, and mechanism for winding said spring, a hammer and mechanism for operating the same, and mechanism for holding the hammer in a state 30 of rest when the bell is not in use.

In the drawings, Figure 1 is an elevation of the base-plate and alarm mechanism and a section of the gong. Fig. 2 is a plan of the same with the gong removed. Fig. 3 is an elevation 35 of the bell complete as adapted to the brake-arm. Fig. 4 is a plan of the winding-button, and Fig. 5 is a perspective view of part of a machine with a bell in both positions.

The base-plate a , Fig. 1, is made with a jaw, 40 a' , for the reception of the handle-bar of the bicycle, and it is provided with a screw-nut, a'' , to press on said bar and clamp the base-plate a and alarm-bell and mechanism in place. The base-plate a , Fig. 3, is made with projecting 45 lugs b and a yoke or strap piece, c , for passing around the brake-arm of the bicycle; and screws d d' are provided for clamping the yoke to the base-plate and holding the plate and bell upon the machine. Into this base-plate a , I secure three or more standards, e , and I provide a plate, f , with openings, into

which the ends of these standards pass and are secured. A section of tubing, g , is upon this plate f , and its upper portion is cut with a male screw fitting a female thread in the 55 opening in the top of the gong h ; and I provide a nut or ring, i , screwing upon the thread of g , to clamp the gong in position. There should be a shoulder on the tube g for the gong to rest upon. 60

The alarm mechanism consists of the spring k , toothed wheel l , ratchet m , pinion n , escape- 65 ment-wheel o , anchor p , and wire and hammer r . The spring k is upon the arbor k' , and said arbor k' has a bearing in the base-plate a and a shoulder at the plate f and it extends up through said plate through the tubing g , and a thread is cut on the end of said arbor for the winding-button s , employed in winding up the alarm. Instead of cutting a screw-thread on the arbor k' , 70 the end may be square and a key or button, s , fitted to it. The whole of this alarm mechanism is contained within the gong and between it and the base-plate, and being so confined is out of sight, is neat and compact, and the bell 75 protects the parts from dust to a large extent. The curved lever t is secured upon the base-plate a by a rivet in such a manner that it is held in place, but may be swung upon the rivet, and this lever has a broad end, to be 80 grasped by the fingers, and I provide a spiral spring, u , with one end secured to a standard, e , and the other end to the end of said lever t , which is turned up at right angles to the main portion. This turned-up end of the lever t 85 takes a bearing against the wire of the hammer r , and the force exerted by the spiral spring u retains the alarm mechanism in a state of rest.

The alarm is operated in the following manner upon the bicycle: The spring k is wound up by turning the button s either before the rider starts out or while he is riding on the road. If he wishes to give an alarm, he presses against the broad end of the lever t , elongating the spiral spring u and releasing the wire and hammer r and alarm mechanism, and so allowing the alarm to sound. A short alarm, a long alarm, and a variety of combinations of short and long alarms may be sounded according to the length of time the pressure is maintained upon the lever t , as the moment the

lever *t* is released the spring returns the lever to its normal position and holds the hammer in a state of rest.

In connection with my alarm a sliding rod 5 and spring secured upon the handle-bar of the bicycle may be used, so that said alarm can be operated without removing the hands from the handle-bar of the machine.

- I claim as my invention—
- 10 1. In a bell for bicycles, the combination, with the gong and base-plate, and mechanism for removably attaching said base-plate to the brake-arm or handle-bar, of striking mechanism within the gong and between it and the base-plate, the button *s* upon the arbor of the main spring and outside the gong for winding
  - 15

up the alarm-spring, and the hand-lever or stop *t* and spring *u* for holding the hammer-wire *r* and stopping the alarm, substantially as set forth.

2. A gong-bell for bicycles, its spring and striking mechanism, in combination with the base-plate and mechanism for removably attaching the same to the brake-arm or handle-bar, substantially as specified.

Signed by me this 27th day of March, A. D. 1883.

HAROLD SERRELL.
